UNITED STATES PATENT OFFICE.

JOSEPH B. HOLDEN, OF SYRACUSE, NEW YORK, ASSIGNOR TO REMINGTON TYPE-WRITER COMPANY, OF ILION, NEW YORK, A CORPORATION OF NEW YORK.

TYPEWRITING MACHINE.

Application filed May 6, 1922. Serial No. 558,951.

To all whom it may concern:

Be it known that I, JOSEPH B. HOLDEN, citizen of the United States, and resident of Syracuse, in the county of Onondaga and 5 State of New York, have invented certain new and useful Improvements in Typewriting Machines, of which the following is a specification.

My invention relates to typewriting machines and more particularly to carriage escapement mechanism, and to the manner of mounting and connecting parts thereof and their actuating means and correlated devices.

15 The main object of my invention, generally stated, is to provide comparatively simple and efficient means of the character specified.

A further object of my invention is to provide a construction such as that referred to, which may be made light in weight without sacrificing efficiency and may be included in a small compact portable machine, affording ready access to the parts nevertheless.

To the above and other ends which will hereinafter appear, my invention consists in the features of construction, arrangements of parts and combinations of devices 30 set forth in the following description and particularly pointed out in the appended claims.

In the accompanying drawings wherein like reference characters indicate corresponding parts in the various views,

Figure 1 is a fore-and-aft vertical sectional view, with parts omitted, of a machine embodying my invention.

Figure 2 is a fragmentary top plan view 40 of the same, with some of the parts disclosed in Fig. 1 omitted.

Figure 3 is a detail fragmentary front view of the combined fulcrum and comb plate and some of the associated parts.

45 I have shown my invention in the present instance embodied in a Remington portable machine, where it aids materially in the production of a light, compact and highly efficient machine. It should be understood, 50 however, that the invention may be embodied in other styles of machines.

Many features of the Remington portable machine are disclosed in the following patents and application: A. W. Smith, Pt. 1,342,513, dated June 8, 1920; J. B. Holden, 55 Pt. 1,386,256, dated Aug. 2, 1921; J. B. Holden, Pt. 1,397,166, dated Nov. 15, 1921; J. B. Holden, Sr. No. 531,649, filed Jan. 25, 1922.

The frame of the machine comprises an 60 outer sheet metal frame 1 surrounding and fixed to an inner frame which includes sheet metal side plates 2 united by a hollow cross bar 3 and a casting 4. The various working parts of the machine are carried by this 65 inner fixed frame. As shown in the above mentioned Smith patent printing key levers 5 are fulcrumed on a fixed rod 6 carried by a bracket 7 secured to the casting 4, and each lever is provided with a finger key 8. The 70 various key levers pass through guide slots 9 in a sheet metal combined guide comb and fulcrum plate 10, best shown in Fig. 3. This guide comb extends across the machine near the front thereof, and is secured 75 to ears 11 on the side plates 2 by screws 12.

The upper portion of the plate 10 is slotted at 13 and 13^a (Fig. 3) to receive and guide the forward sub-levers of the type actions and also the space key levers, each of 80 which fulcrums on the bottom wall of its respective slot, as will hereinafter appear. A keeper plate 14 prevents the parts from being dislodged from their fulcrums, as disclosed in my above mentioned applica- 85 tion.

Each key lever has the lower end of a link 15 pivoted thereto at 16, whereas the upper end of each link is pivoted at 17 to a sub-lever 18. The forward end of each of 90 these sub-levers is fulcrumed on the plate 10 as explained above. Each sub-lever 18 is also pivoted at 19 to a link 20, pivoted at its upper end at 21 to a second sub-lever 22. These latter are pivoted at 23 on a seg- 95 mental casting 24 formed integral with the casting 4. The inner ends of the sub-levers 22 are formed with segmentally arranged rack teeth 25 that mesh with corresponding rack teeth 26 on the heels of the type bars. 100 The type bars 27 are pivoted at 28 to a segment which constitutes part of the cast-

ing 4. Each type bar carries a lower case type *a* and an upper case type *b*. A depression of the printing key 8 is effective to move the corresponding type bar downwardly and rearwardly to strike against the top face of a platen 29 with either of the types *a* or *b*, depending on the case shift position of the platen.

The platen is supported by a carriage for traveling movement across the machine and for case shifting movement fore-and-aft of the machine, as disclosed in my above mentioned Patent No. 1,386,256, and as will now be set forth.

15 The sheet metal bed 30 of the carriage, which supports the platen 29, has its edge portions bent to form raceways 31 and 32 in which crossed bearing rollers 33 are received. These rollers are also received in 20 ways 34 and 35 formed in plates secured to an aluminum casting 36. This casting forms a support for the carriage and over which the latter travels, and with which it moves fore-and-aft of the machine in its 25 case shifting movements. The support 36 constitutes a portion of a case shift frame and carries depending slotted lugs 37 in which are pivoted, at 38, the upper ends of parallel arms 39 fixed to a rock shaft 40. 30 Said shaft is mounted at its reduced ends in bearing openings in the side plates 2 of the inner fixed frame. In this manner the carriage support 36, and the case shift frame of which it forms part, are supported at the 35 rear of the machine for case shift movement. The support 36 is detachably fixed by screws 41 to horizontally disposed sheet metal flanges 42, each formed as a part of a side member, plate or bar 43 that extends 40 fore-and-aft of the machine. The forward end of each member 43 is pivoted at 44 to a depending link 45, pivoted at its upper end on a pivot pin 46 which extends in from the companion side plates 2. A cotter pin 45 47, extending through an opening in each pin 46, prevents an accidental detachment of the associated link 45 from its pin.

Suitable stops 48, adjustable on each side plate 2, co-operate with a stop 49, secured at 50 to the companion member 43 of the shift frame, to arrest its case shift movements.

Any suitable key controlling means may be employed to shift the case shift frame. In the present instance a pin 51 projects 55 from the left-hand bar 43 and coacts with the depending arm of an angular lever 52. This lever is pivoted at 53 to the left-hand side plate 2 of the inner fixed frame. A depending link 54 is connected at its upper 60 end to a forwardly projecting arm of the lever 52; the lower end of the link being pivoted, as indicated at 55, to a shift key lever 56 carrying a shift key 57. The lever 56, like the printing key levers, is fulcrumed 65 at 6 on a fixed part of the machine. A de-

pression of the key 57 is effective to move the case shift frame with the parts carried thereby rearwardly from the position shown in Fig. 1, and present the platen in position to receive the impact of the upper case types *b* on the type bars.

Aside from the type actions and space key, most of the other working parts are mounted to shift with the carriage, and thus maintain the same relative arrangement in either case position of the carriage, as will now be pointed out.

The feed rack 58 is carried by a sheet metal plate 59, pivoted at 60 to the carriage for movement into and out of engaging position. It will be seen that the feed rack is arranged at a lower level than the carriage support 36, and has its teeth extending forwardly for co-operation with the substantially horizontally disposed feed dogs 61 and 62. These are carried by a substantially horizontally disposed dog rocker arranged beneath the carriage support 36, the carriage and platen, and extending fore-and-aft of the machine. The dog rocker 60 comprises two fixedly connected sheet metal plates 63 and 63^a. One of these plates 63 is formed with depending ears 64, apertured to receive the reduced pivot bearing ends 65 of two screws 66. These screws are threaded into tapped openings in depending ears 67 of a sheet metal bracket 68, secured by screws 69 to the bottom of the carriage support 36. Lock nut 70 holds the pivot screws 66 against accidental displacement. A rearwardly projecting finger 71 on the bracket 68 coacts with the dog rocker to limit the upward movement of the rear end thereof. A pin 72 projects up from the plate 63^a of the dog rocker and is surrounded by a coiled expansion spring 73 that bears at its lower end against the dog rocker. The upper end of the spring bears against the carriage support 36; the spring passing through a hole 74 (Fig. 2) in the bracket 110 plate 68 to reach the support, and the side walls of the hole 74 together with the pin 72 retain the spring against lateral displacement.

The plate 63^a of the dog rocker is extended to provide a forwardly projecting integral arm 75, by which the dog rocker is actuated from the printing keys and from the space key through separate trains of connections.

I will first describe the train of connections by which the dog rocker is actuated at each operation of a printing key.

Each key lever 5 coacts with the bendably adjustable projections 76 on a universal bar 125 77, connected at its ends by spot-welding or otherwise with side members 78 of a sheet metal universal bar frame. This frame in addition to the arms 78 and the universal bar includes a cross bar 79 spot-welded to 130

inwardly projecting integral portions 78^a on the members 78. The side members 78 of the frame are pivoted at 79^a to the side members 43 of the shift frame, so that the 5 entire universal bar frame partakes of the case shifting movements of the shift frame. A sheet metal bracket 80 is secured by screws 81 to the cross bar 79, and is formed with an integral arm 82 that extends forwardly, 10 where connection is made with the universal bar 77 by spot-welding or otherwise. The arm 82 also projects rearwardly from its bracket 80 and carries a laterally projecting pin or contact 83 at the rear end portion 15 thereof. This contact is arranged beneath a laterally projecting integral lug or contact 84 on the arm 75 of the dog rocker; there being a lost motion between the contacts before the contact 83 coacts with the contact 84.

It will be understood that the depression of a printing key 8 is effective to depress the universal bar, thus rocking its frame and swinging the contact 83 up. When the contact 83 reaches the contact 84, the dog rocker will be rocked, moving downwardly at its rear end and moving the dog 61 out of the rack and the dog 62 into engagement therewith. On the return of the dog rocker the carriage will advance one step under the power applied thereto by a spring drum 85. This spring drum is carried by the carriage support 36, and is connected to the carriage by a cord 86 which runs over a pulley 87 and is connected at one end to the drum and at the other end 88 to the carriage.

As hereinbefore indicated, the escapement is controlled from the space key 89 by a separate train of connections which comprises two sheet metal levers 90 fixedly connected at their forward ends to the space key, and each formed as shown in Fig. 1 with an inverted substantially V-shaped portion 91 received in a slot 13^a in the combined fulcrum and comb plate 10. Each of the slots 13^a is substantially twice the width of a slot 13, so that a lever 90 and the adjacent sub-lever 18 may be received in the same slot 13^a. These levers 90 straddle the plate 10 and fulcrum on the bottom walls of the slots 13^a and extend rearwardly and downwardly from the plate 10. The rear ends of these levers are united by a cross bar 92 fixed thereto by screws 93. The space key 89, levers 90 and cross bar 92, as viewed from above, constitute a rectangular frame fulcrumed intermediate its ends on the plate 10, and returned to normal position by two springs 92^a; one connected to each lever 90. Fixed to the cross bar 92 intermediate its ends, and projecting rearwardly and upwardly therefrom, is a sheet metal arm 94. This arm, in the present instance, has a hole therethrough shaped to conform to the angular cross-section of the bar 92, which bar

extends through said hole. The arm 94 also has a laterally projecting integral foot piece 95 extending at right-angles to the plane of the arm and fixed to the cross bar 92 in any suitable manner, as by spot-welding. The 70 rear end of the arm 94 has an upwardly extending open-ended slot 96 therein that is inclined slightly to the rear from the lower to the upper end thereof. An upright link 97 is pivoted at its lower end by a cotter pin 98 to the arm 75 of the dog rocker, whereas the upper end of the link carries a laterally projecting pin 99 that projects into the slot 96 in the arm 94.

This construction is such that in the shifting movement of the dog rocker with the carriage support 36, the lower end of the link 97 will turn around the axis of the pin 99, which pin at this time turns in its seat at the lower end of the slot 96 without affecting the operative connection between the space key and dog rocker. In either the normal, or case shifted position of the dog rocker, an actuation of a printing key will cause the dog rocker to oscillate it in the 90 manner described above. At this time the pin 99 will move up freely in the slot 96, while the space key and the remainder of its train of connections to the dog rocker stand at rest. On the other hand, when the dog rocker is actuated by the space key the contact 84 on the dog rocker will move upwardly away from the contact 83 and the train of actuating connections from the universal bar will remain at rest. Therefore, 95 when the dog rocker is actuated from a printing key it is unnecessary to move the separate train of connections to the space key, and vice versa, thus relieving the resistance to the touch on the keys to this extent.

A ribbon vibrator 100 is mounted for sliding movement in an inclined plane on a bracket arm of a type guide fixed to the casting 4. The vibrator is detachably connected at 102 to a link 103 pivoted at 104 to the upper free end of a sheet metal arm 105. This arm forms part of an actuating device 106 pivoted at 107 to a sheet metal bracket 108 secured to the carriage support 36. This device 106, and the manner of controlling it and regulating the extent of throw of the vibrator, is the same, or substantially the same, as disclosed in my hereinbefore mentioned Patent 1,397,166. Thus, the slots in the parallel arms of the device 106 receive a bent connecting wire 109 controlled for longitudinal setting movement by a member 109^a controlled by a key not shown. This wire also extends through a slot in an arm 110 which projects rearwardly from the bracket 80 on the universal bar frame, thus forming an operative connection between the universal bar frame and the ribbon actuating device 106. It follows therefore that a case shifting movement of the carriage is 130

effective to produce a corresponding shifting movement of the vibrator 100, the arm 105, the actuating device 106, the rod 109, the arm 110 and universal bar frame, fore-and-aft of the machine with the carriage.

An actuation of the universal bar by any printing key is effective to operate the vibrator, but an actuation of the space key is ineffective on the vibrator.

10 The vibrator and the parts connected therewith are returned from their actuated position by a contractile spring 111 connected at one end to the arm 105 and at the other end to the cross bar 79 of the universal bar frame.

It will be understood from the foregoing that the escapement devices and means for controlling the latter and the ribbon vibrator, are situated near the bottom of the machine 20 below the system of key levers, where they are readily accessible from the bottom of the machine; that the mechanism is light in construction; may be easily embodied in the comparatively small space available in the 25 small compact machine in which it is employed, and the mechanism in use has proved highly efficient and durable.

What I claim as new and desire to secure by Letters Patent, is:—

30 1. In a typewriting machine, the combination of a case shift frame, a platen carrier carried by said case shift frame, a feed rack carried by said platen carrier and shiftable therewith, a dog rocker arranged beneath said platen carrier where it is accessible from the bottom of the machine, said dog rocker being shiftable with said case shift frame and feed rack, and a universal bar shiftable with said case shift frame and 35 operatively connected with said dog rocker.

2. In a typewriting machine, the combination of a case shift frame, a platen carrier carried by said case shift frame, a feed rack carried by said platen carrier and shiftable therewith, a dog rocker arranged beneath said platen carrier where it is accessible from the bottom of the machine, said dog rocker being shiftable with said case shift frame and feed rack, a universal bar shiftable with said case shift frame and operatively connected with said dog rocker, a space key carried by a fixed part of the machine, and an independent train of connections between said space key and said 50 dog rocker.

3. In a typewriting machine, the combination of a case shift frame including a carriage support, a platen carriage mounted on and adapted to travel along said support, a feed rack carried by the carriage and located at a lower level than said support, a substantially horizontally disposed dog rocker carried by and arranged beneath said support where it is accessible from the bottom of the machine, keys carried by a fixed

portion of the machine, and means controlled by said keys for actuating said dog rocker.

4. In a typewriting machine, the combination of a case shift frame including a carriage support, a platen carriage mounted on and adapted to travel along said support, a feed rack carried by the carriage and located at a lower level than said support, a substantially horizontally disposed dog rocker carried by and arranged beneath said support where it is accessible from the bottom of the machine, printing keys carried by a fixed portion of the machine, means controlled thereby for actuating the dog rocker, a space key carried by a fixed portion of the machine, and a separate train of connections therefrom to the dog rocker for actuating the latter independently of the connections from the printing keys. 75 80 85

5. In a typewriting machine, the combination of a combined fulcrum and comb plate at the front of the machine, a plurality of spaced key levers fulcrumed on an edge of and guided by said plate, a space key connecting said levers, escapement devices, and means controlled by said space key levers for operating said escapement devices. 90 95

6. In a typewriting machine, the combination of a combined fulcrum and comb plate, a space key lever having a substantially V-shaped recess therein by which it may straddle and fulcrum on said plate and be guided thereby, a space key connected with said lever, and escapement devices controlled by the lever. 100

7. In a typewriting machine, the combination of a combined fulcrum and comb plate, space key levers fulcrumed on and guided by said plate, a space key connecting said levers, a cross bar uniting said levers, an arm on said cross bar, and escapement devices controlled by said arm. 105

8. In a typewriting machine, the combination of a combined fulcrum and comb plate, space key levers fulcrumed on and guided by said plate, a space key connecting said levers, a cross bar uniting said levers, an arm on said cross bar, a dog rocker, a link intermediate said arm and dog rocker and operatively connected to one of said parts by a pin and slot connection. 110 115

9. In a typewriting machine, the combination of a case shift frame mounted for case shifting movement fore-and-aft of the machine, a dog rocker mounted to shift therewith, a space key mounted on a fixed part of the machine, and intermediate operative connections between said space key and dog rocker including a link shiftable fore-and-aft of the machine at one end with the dog rocker without altering the control of the dog rocker by the space key. 120 125

10. In a typewriting machine, the combination of a case shift frame mounted for 130

case shifting movement fore-and-aft of the machine, a dog rocker mounted to shift therewith, a space key mounted on a fixed part of the machine, and intermediate operative connections between said space key and dog rocker including a link shiftable fore-and-aft of the machine at one end with the dog rocker without altering the control of the dog rocker by the space key, and a pin and slot connection between the link and a space key actuated member to permit an actuation of the dog rocker independently of the space key.

11. In a typewriting machine, the combination of a case shift frame mounted for case shifting movement fore-and-aft of the machine, a dog rocker mounted to shift therewith, a space key mounted on a fixed part of the machine, an operating arm movable up and down and controlled by said space key, and a link having a pivotal connection at one end with said arm and at the other end with said dog rocker and adapted at the last mentioned end to move fore-and-aft of the machine with the dog rocker in the case shifting movements of the latter.

12. In a typewriting machine, the combination of a case shift frame mounted for case shifting movement fore-and-aft of the machine, a dog rocker mounted to shift therewith, a space key mounted on a fixed part of the machine, an operating arm controlled by said space key and movable up and down, and a link having a pivotal and also a sliding connection with one of said rocker and arm members and a pivotal connection with the other, whereby the dog rocker may receive a movement fore-and-aft of the machine with the case shift frame independently of said arm and also may receive an operating movement independently of the arm and space key as well as an operating movement by the space key.

13. In a typewriting machine, the combination of a case shift frame, a dog rocker mounted to shift therewith, a space key mounted on a fixed part of the machine, and intermediate operative connections between said space key and dog rocker including space key levers, a bar which unites said levers, an arm carried by said bar and having a slot therein, and a link having at one end a pin seated in said slot for pivotal and also for sliding movements and pivoted at the other end to the dog rocker, whereby one end of the link moves with the dog rocker as the latter shifts with the case shift frame and the dog rocker may be moved independently of said arm and space key.

14. In a typewriting machine, the combination of a dog rocker, a universal bar, means controlled thereby for actuating said dog rocker, a space key, and an independent train of connections from the space key to the dog rocker for actuating the latter inde-

pendently of the universal bar, said connections comprising space key levers, a cross bar that unites said levers, an arm carried by said cross bar and having a slot therein, and a link carrying at one end a pin which works in said slot and pivoted at the other end to the dog rocker.

15. In a typewriting machine, the combination of a dog rocker having a contact, a universal bar having an arm that carries a contact which moves up and down and coacts with the contact on the dog rocker to actuate it and permit a movement of the rocker independently of said arm, a space key, and an independent train of connections between the space key and said dog rocker for actuating the latter from the space key independently of the universal bar, said connections comprising an actuating arm movable up and down and controlled by the space key and connections between said arm and the dog rocker including a pin-and-slot connection that enables the rocker to move independently of said arm under control of the universal bar but enables the space key to move the rocker at will.

16. In a typewriting machine, the combination of a case shift frame, a dog rocker shiftable therewith, a universal bar shiftable with said case shift frame, a space key carried by a fixed part of the machine, operative connections between the universal bar and the dog rocker to actuate the dog rocker but permit an actuation of the latter independently of said universal bar, and a separate train of connections intermediate said space key and dog rocker including a link which permits a movement of the dog rocker with the case shift frame.

17. In a typewriting machine, the combination of a case shift frame; a dog rocker shiftable therewith; a universal bar shiftable with said case shift frame; a space key carried by a fixed part of the machine; operative connections between the universal bar and the dog rocker to actuate the latter but permit an actuation thereof independently of said universal bar; and a separate train of connections intermediate said space key and dog rocker including a link which permits a movement of the dog rocker with the case shift frame, and a pin-and-slot connection between said link and a coacting part that enables the rocker to be actuated by the universal bar independently of the space key.

18. In a typewriting machine, the combination of a case shift frame; a dog rocker shiftable therewith; a universal bar shiftable with said case shift frame; a space key carried by a fixed part of the machine; an arm on the universal bar and carrying a contact which coacts with a contact on the dog rocker to actuate the latter but permit an actuation thereof independently of the space key.

said arm; and a separate train of connections intermediate said space key and dog rocker including a link which permits a movement of the dog rocker with the case shift frame, and a pin-and-slot connection between said link and a coacting part that enables the rocker to be actuated by the universal bar independently of the space key.

19. In a typewriting machine, the combination of printing key levers pivoted to a fixed portion of the machine; a case shift frame; a ribbon vibrator; a dog rocker; and a universal bar controlled by said key levers, a link intermediate said universal bar and dog rocker, the vibrator, dog rocker, universal bar and one end of the link all being shiftable with the case shift frame; and actuating means controlled by said universal bar for operating said ribbon vibrator and which operating means also are shiftable with the case shift frame.

20. In a typewriting machine, the combination of a case shift frame; a ribbon vibrator; a dog rocker and a universal bar controlling the dog rocker, all shiftable with the case shift frame; actuating means controlled by said universal bar for operating said ribbon vibrator, and which operating means also are shiftable with the case shift frame; a space key mounted on a fixed part of the machine; and a separate train of actuating connections including a link intermediate said space key and dog rocker, and which link permits a shifting of the dog rocker with the case shift frame independently of the space key.

21. In a typewriting machine, the combination of a case shift frame; a dog rocker shiftable therewith; a universal bar shiftable with said frame and operative to actuate the

dog rocker and permit an actuation thereof independently of the universal bar; a ribbon vibrator and actuating means therefor, both shiftable with said frame and actuated by the universal bar; a space key carried by a fixed part of the machine; and a separate train of actuating connections including a link between said space key and dog rocker, said connections enabling the dog rocker to be shifted with the shift frame independently of the space key, and enabling the dog rocker to be actuated by and independently of the space key.

22. In a typewriting machine, the combination of a case shift frame; a dog rocker shiftable therewith; a universal bar shiftable with said frame and operative to actuate the dog rocker and permit an actuation thereof independently of the universal bar; a ribbon vibrator and actuating means therefor both shiftable with said frame and actuated by the universal bar; a space key carried by a relatively fixed part of the machine; and a separate train of actuating connections between said space key and dog rocker that enables the dog rocker to be shifted with the shift frame independently of the space key, and enables the dog rocker to be actuated by and independently of the space key, said actuating connections including a link shiftable at one end with the case shift frame and connected to a cooperative part by a pin-and-slot connection.

Signed at Syracuse, in the county of Onondaga and State of New York, this 2 day of May, A. D. 1922.

JOSEPH B. HOLDEN.
